(No Model.)

R. McD. DIXON.
MATCH BOX.

No. 605,276.

Patented June 7, 1898.

UNITED STATES PATENT OFFICE.

RANDALL McDONALD DIXON, OF PHILADELPHIA, PENNSYLVANIA.

MATCH-BOX.

SPECIFICATION forming part of Letters Patent No. 605,276, dated June 7, 1898.

Application filed September 18, 1897. Serial No. 652,169. (No model.)

To all whom it may concern:

Be it known that I, RANDALL McDONALD DIXON, a resident of Philadelphia, in the county of Philadelphia and State of Pennsylvania, have invented certain new and useful Improvements in Match-Boxes; and I do hereby declare the following to be a full, clear, and exact description of the invention, such as will enable others skilled in the art to which it app pertains to make and use the same.

My invention relates to an improvement in match-boxes, the object of the invention being to provide a match-box for use of bicycle-riders which can be readily applied to the belt of the rider and from which the rider can readily remove the matches, one at a time, while the bicycle is in motion without moving his body and without danger of deranging the supply of matches in the box.

A further object is to provide a match-box for the purpose stated which shall be simple in construction, easy and cheap to manufacture, and which shall be effectual in all respects in the performance of its functions.

With these objects in view the invention consists in certain novel features of construction and combinations and arrangements of parts, as hereinafter set forth, and pointed out in the claims.

In the accompanying drawings, Figure 1 is a side elevation of my improved match-box. Fig. 2 is an end view with the face-lid open. Fig. 3 is a plan view with the face-lid open. Fig. 4 is a face view with the face-lid closed and the end lid open. Figs. 5 and 6 are detail views.

A represents the body of my improved match-box, which may be conveniently made of light sheet metal. The box is provided with a face-lid 1, which is connected at one edge thereto by means of a spring-hinge 2, adapted to maintain said lid closed or to maintain it open to its full extent. The lid 1 is also maintained securely closed by means of a lip 3 on the lid and adapted to enter a notch or recess 4 in the body of the box. The lid 1 is also made with two (or more) hooks 5, which are preferably formed integral therewith and are adapted to be placed on the belt of a bicycle-rider.

One end of the box A is provided with a hinged lid 6, provided with a spring 7, adapt-

ed to maintain the lid normally closed or to hold it open to its full extent when it is desired to remove a match from the box.

55

The box A is provided internally, at the sides thereof, with guides 8 for the accommodation of a comb 9. The comb 9 comprises a plate 10, having a series of spring fingers or teeth 11 adapted to bear upon the matches in the box. A lip 12 projects from the plate 10 and serves as a finger-piece to be grasped by the user for removing the comb when it is desired to fill the box with matches.

When the box is to be filled, both lids will be opened and the comb removed, as above intimated, when the matches can be placed in said box in regular order, after which the comb will be slid in place in the guides provided for it and the fingers permitted to bear upon the matches.

When it is desired to remove a match, the user will open the end lid 6 with one hand and remove a single match, whereupon the spring-finger of the comb which pressed against said match will press upon the succeeding match in the box and prevent its withdrawal, and the various spring-fingers will combine to prevent the derangement of the matches in the box when one is removed.

80

My improvements are very simple in construction, cheap to manufacture, easy to manipulate, and are effectual in all respects in the performance of their functions.

Slight changes might be made in the details of construction of my invention without departing from the spirit thereof or limiting its scope, and hence I do not wish to limit myself to the precise details herein set forth.

Having fully described my invention, what I claim as new, and desire to secure by Letters Patent, is—

1. The combination in a match-box, of a body portion having a lid at one end, guides in said body portion and a comb removably placed in said guides and having spring-fingers to bear against the matches in said body portion, substantially as set forth.

2. The combination in a match-box, of a body portion having a lid at one end, guides in the other end of said body portion, a comb having spring-fingers to bear on matches in the body portion and adapted to slide freely in said guides, and a finger-piece on said comb

whereby to remove it from the body portion when the box is to be filled with matches, substantially as set forth.

3. As an article of manufacture, a matchbox comprising a main body portion or receptacle having a hinged side and end, and a removable comb.

In testimony whereof I have signed this specification in the presence of two subscribing witnesses.

RANDALL McDONALD DIXON.
